JOSEPH O'CONNELL AND HAROLD HAMILTON KERR, OF KENSINGTON, VICTORIA,
AUSTRALIA

WOODEN BARREL OR DRUM FOR CHURNS

Application filed November 29, 1929, Serial No. 410,449, and in Australia January 22, 1929.

This invention has been devised to provide an improved wooden barrel or drum for churns employed in the manufacture of butter and treatment of cream. With the present construction of wooden churns the members are liable to expand or contract from the effects of moisture and stresses and strains during operations and the varying of the temperature within the container.

10 The object of the invention is to provide a wooden churn barrel or drum, the heads forming the end walls being constructed and arranged to ensure that an even expansion or contraction takes place so that the heads will 15 retain a predetermined shape and will not become distorted by usage as is usual when the barrel is formed otherwise than according to our invention.

In describing our invention we shall refer 20 to it as embodied in the barrel or drum of a rotary churn.

In order to more readily understand the invention reference will now be made to the accompanying drawing in which:—

25 Figure 1 is an end view showing the construction of a churn barrel in accordance with our invention.

Figure 2 shows in detail how the staves are joined with a head end of the barrel.

30 Figure 3 shows a detail of the radial members or sectors forming the heads of the barrel and how each member is joined to the next and

35 Figures 4 and 5 are detail views of alternative jointings of radial members.

Figure 6 is a perspective view of one of the radial members forming the subject of our invention.

The wooden members 5 comprising the 40 end walls or heads 6 of the barrel or drum of the churn are oblong sectors disposed radially (see Figure 1) and each member 5 tapers toward the center of the barrel or drum, i. e., they are wider at the ends 7 than

45 the ends 8, and each member is preferably provided with a tongue 9 on one longitudinal edge, and a groove 10 in the opposite longitudinal edge, said tongue and groove being of any desired shape, either a wedge-shaped tongue and groove as in Figures 4 and 5, or

a rectangular tongue and groove, as in Figure 3. The abutting edges of the members 5 radiate from the centers of the heads, and the connecting joints of the members comprise the tongue of one member fitting into the groove of the next and abutting member.

It will be seen that the tongues and grooves interlock each member 5 with the next, in such manner as to prevent both inward and outward displacement or bulging of any member, and maintain the sides of the head, formed by said members, in predetermined planes.

The radial oblong members 5 are so proportioned that their length is much greater than the width of their outer ends. The grain of the wood from which the oblong members 5 are made, extends lengthwise, and not crosswise of said members, so that expansion of the members 5, caused by absorption of moisture, is mainly crosswise of said members and causes a uniform tightening of the joints formed by the abutting edges of the members. The described proportions of the members 5 enables the members with the grain extending lengthwise, to be prepared with a minimum of waste by diagonally sawing a relatively wide board to convert it into two members 5.

In some cases the described tightening may be sufficient to prevent both inward and outward displacement of bulging of any member 5, so that the abutting edges of the members 5 may be plain, that is, without either tongues or grooves, although we prefer in any case, to provide the tongues and grooves.

The outer ends 7 of the radially disposed members 5 fit into an internal groove or channel 11 formed in the stave members 12 comprising the cylindrical body of the barrel or drum.

Each of the stave members 12, has, near each end, a groove 11 which receives end tongues 13 on the wider ends of the radial members 5, so that when said radial members are in position to form a disk, and the stave members 12 are assembled on and secured to the periphery of the disk, the whole structure becomes rigid as will be obvious.

The longitudinal expansibility of the mem-

bers 5, although less than the crosswise expansion, is sufficient to tighten the joint formed by the end tongues 13 and the grooves 11. The forces of expansion are so distributed throughout the head, that any expansion is general and not local.

The inner ends 8 of the members 5 collectively form a circular opening, adapted to receive a disk or bearing (not shown), supporting a stub axle of the actuating mechanism.

We claim:

1. A churn barrel comprising a cylindrical body, and discoidal heads, each composed of tapered oblong sectors, whose longitudinal edges abut each other and radiate from the center of the head, the wider outer ends of the sectors being interlocked with an end portion of the body, and the abutting edges tongued and grooved, so that each sector is interlocked with the next to prevent both inward and outward sidewise displacement of the sector and maintain the sides of the head in predetermined planes.

2. A churn barrel comprising a cylindrical body, and discoidal heads, each composed of tapered oblong wooden sectors whose longitudinal edges abut each other and radiate from the center of the head, the wider outer ends of the sectors being interlocked with an end portion of the body, the sectors being proportioned so that their length is much greater than the width of their outer ends, the grain of the wood extending lengthwise of the sectors so that expansion of the sectors, caused by absorption of moisture, is mainly crosswise of the sectors and causes a uniform tightening of the joints formed by the abutting edges.

In testimony whereof we have affixed our signatures to this specification.

JOSEPH O'CONNELL.

HAROLD HAMILTON KERR.
